UNITED STATES PATENT OFFICE.

JOHN F. GILCHRIST, OF CHICAGO, ILLINOIS.

DINING-TABLE CONNECTOR.

1,309,406.

Specification of Letters Patent.

Patented July 8, 1919.

Application filed August 13, 1917, Serial No. 185,823. Renewed March 27, 1919. Serial No. 285,639.

To all whom it may concern:

Be it known that I, JOHN F. GILCHRIST, a citizen of the United States, residing at Chicago, in the county of Cook and State of Illinois, have invented a certain new and useful Improvement in Dining-Table Connectors, of which the following is a specification.

My invention relates to connectors for electrical appliances used on dining-tables. It is well known that the use of electric candles or toasters, percolators, egg boilers, and the like, upon dining or other cloth covered tables presents a problem which has never been heretofore solved with complete satisfaction. Assume, for instance, a dining-table lighted by a number of electric candles placed upon the table cloth. No perfectly satisfactory means has been heretofore devised for supplying the electric energy to them. One known method is to form a hole near the center of the table and pass the supply conductors up through it and up through the table cloth. This has the disadvantage of permanently disfiguring the table. Another method is to lead the supply conductors up over the edge of the table above the cloth. But in such case the supply conductors are exposed on the top of the cloth. Worse still, however, is the fact that said conductors hang upon the outside of the hanging portion of the table cloth, which is not only unsightly, but actually dangerous because both guests and servants are apt to become entangled in the hanging portion of the conductors and drag things to the floor. One of the chief purposes in using table candles, for example, is to produce an artistic and decorative effect, and it is important, therefore, that the connector be not only safe and efficient but that it be of attractive appearance in every respect. The object of my invention is to provide means whereby table candles or other electric devices may be safely and decoratively supplied with current.

I accomplish my object by the construction illustrated in the accompanying drawings, in which—

Figure 1 is a vertical section of the assembled device on the line 1—1, Fig. 2.

Fig. 2 is a bottom plan partly in section on the line 2—2, Fig. 1.

Fig. 3 is a top plan of the bottom plate or disk showing the supply conductors attached thereto.

Fig. 4 is a sectional elevation showing the parts of the device separated from each other to more clearly illustrate their construction and coöperative relationship. 60

Fig. 5 is a perspective of the parts above the table cloth as they will appear in use.

Fig. 6 is a cross section of the supply conductors on the line 6—6, Fig. 3.

Similar numerals refer to similar parts 65 throughout the several views.

In the form selected to illustrate the invention, the bottom plate 1 is preferably of circular outline and consists of a thin sheet of fiber or other insulating material. 70 This lies loosely upon the top of the table and may have felt or other fabric on the bottom for preventing it from scratching the table. Standing upright upon this plate is a cylindrical block 2 of insulating material, having an annular contact 3 surrounding its base, and a conical contact 4 surmounting it. The parts 3 and 4 represent opposite poles and are connected respectively to the supply conductors 6 and 8. 80 Said conductors are so constructed as to be extremely flat and thin. In the preferred form, they consist, as shown in Figs. 3 and 6, of a large number of small wires arranged side by side and inclosed within a sheath of 85 insulating material. If desired, these conductors may be brought together at a short distance from the center of the plate 1 and inclosed within an outer sheathing 9 to form a supply cord. The precise composition and 90 construction of the supply cord is immaterial, the important characteristic being that it is flexible and thin enough to lie upon the table beneath the table cloth without making an appreciable ridge in the cloth. 95

The conductors 6 and 8 are here shown connected to the respective contacts or terminals 3, 4 by means of straps 10 and 12 of brass or other conductive material. The strip 12 is shown in Figs. 1 and 4 to be 100 screwed onto the lower end of the stem 13 of the center contact 4. Plate 1 has a slot 14 for accommodating the supply conductors 6 and 8, as best shown in Fig. 3.

From the foregoing it will be seen that 105 the plate 1 is slotted to accommodate the ends of the supply conductors and has an upstanding post with a center terminal connected to one of the supply conductors and a ring terminal connected to the other supply conductor, the ring terminal being insulated from the center terminal. 110

When the device is in use, the table cloth 16 will overlie plate 1, the cloth preferably having an eyelet 17 for accommodating the terminal post. The parts which lie above the table cloth may be considered as constituting a cap. In the construction illustrated, one of the principal parts of the cap is the dome 20 which consists preferably of sheet metal of ornate configuration, silver plated or otherwise treated to give it an attractive appearance. It is provided at the bottom with a plurality of connectors, which in the design shown are of standard type, having sockets 21 adapted to receive the plugs 26. In the present case there are four of these connectors, equally distributed, and the sockets are connected in series by conductors 22 arranged within the dome and, therefore, concealed by it. By preference, the dome has a vertical annular flange 24 at the bottom which is cut away to accommodate the sockets in the manner indicated. The plugs 26 are connected to conductors 27, which lead to the candles or other appliances. As these sockets and connector plugs are well known commercially, a detailed description of them is unnecessary. Their specific form and construction may be considerably varied without departing from the spirit of the invention. It is best, however, that they be comparatively flat so as to lie upon the cloth without occupying much space, and that they radiate from the center of the cap.

The ends of the conductors 22 are connected to binding screws 30, 31. Screw 30 is connected by a strap 32 to a center block 33 which is countersunk to receive and make electric contact with the center contact 4 of the post. Screw 31 is connected by a strap 34 to the ring 35, which is provided with a number of downwardly projecting spring fingers 36, best shown in Figs. 1 and 4. Said fingers are so formed that when lowered onto the post, they will make electric contact with ring 3. The block 33 and fingers 36 are suitably insulated from each other and secured in any suitable manner to the inside of the dome 20. In the particular construction illustrated, a platform 38 of insulating material is fastened within the dome by a stud 39 which is screw threaded and passes up through the center of the dome to a semi-spherical nut 40 by which the parts are held assembled.

In operation, the plate 1 is first laid upon the table, usually near the center. The supply conductors 6, 8 are then led to the edge of the table, then down around the edge and finally to the supply outlet, usually found either in the center of the dining floor beneath the center column of the table, or at some convenient point in the base board of the room. In any event, the supply conductors may be led directly from the edge

of the table to the center leg or column which supports the table, and thence to the outlet, thus avoiding the danger of a guest or attendant becoming entangled in the conductor and dislodging the device. The table cloth is then laid over plate 1, the center post 3, 4 passing up through the eyelet 17 in the cloth. Thus the cloth hides everything but the center post which is small. While the dimensions may be varied, I have found that the center post need be no more than $\frac{3}{8}$ of an inch in diameter and $\frac{1}{2}$ inch high. These parts may be made even smaller if desired. The center cap, consisting of the dome 20, the sockets 21, and attached parts, is then lowered onto the post, whereupon the spring contact fingers 36 automatically engage the ring terminal 3, while the center block 33 engages the center terminal 4. This renders the socket terminals alive so that when the plugs 26 are inserted, their conductors 27 which lead to the candles or heating appliances, are rendered electrically alive.

The dome 20, which may be made quite small, if desired, is the only thing visible above the table cloth with the exception of the connectors 26, and as the dome may be plated to give the appearance of frosted silver or other attractive finish, the device is decorative and adds to the appearance of the table. The dome and attached parts, which for convenience I have collectively termed the "cap" may be removed at any time by simply lifting it off, whereupon the only thing visible will be the post 3, 4 which, as it is very small, may be readily concealed by some other kind of table decoration. The post itself and its supporting plate 1, being unattached to the table, may be removed at any time. As the table cloth is not attached to any part of the device, there is nothing to prevent the removal of the cloth as soon as the cap is removed.

It will be understood that while I have shown a multiplex cap having four different connectors, the number may be increased or decreased by the manufacturer to meet different conditions. It will also be understood that the number of elements, especially those structural parts inside of the dome, may be considerably varied without exceeding the scope of the invention.

Having thus described my invention, what I claim as new and desire to secure by Letters Patent, is:

1. A dining table cluster having a base plate adapted to lie on the table beneath the table cloth, a cap adapted to overlie the table cloth, a plurality of electric terminals fastened to said cap, and interfitting elements of considerable diameter for guiding the cap to central position over the base plate, said interfitting elements being at the center of the device, and one of them having

converging sides for assisting to center the two parts.

2. A dining table cluster having a base plate adapted to lie on the surface of the table beneath the cloth, a cap adapted to overlie the table cloth, a plurality of plug and socket connectors radiating from the cap and extending horizontally, and mating elements, one fastened to the base plate and 10 projecting upward from it and the other fastened to the cap and projecting downward from it, one of said mating elements having an approximately conical surface and the other being chambered to receive it to 15 thereby readily guide the cap to central position over the base plate, supply conductors, and electric connections whereby when the cap is in place upon the base plate, the connectors will be put in circuit with the supply conductors.

3. A dining table cluster having a base plate adapted to lie on the table, a cap adapted to overlie the table cloth, a plurality of plug-and-socket connectors, radiating 25 from the cap in a horizontal direction, and a cone and a socket, one fastened to the base plate and the other to the cap and being of considerable diameter, whereby, when the cap is lowered, it will automatically be centered relatively to the base plate, supply conductors, a ring contact, and a finger, one fastened to the base plate and the other to the cap in position to mutually engage when the cap is lowered onto the base plate, the 35 ring and finger and the cone and socket being conductive and connected to the supply conductors, and plug-and-socket connectors for establishing the circuit when the cap is lowered onto the base.

4. In a connector for electric appliances to be used upon a dining table, a metallic cap having a connector for energizing a table appliance, a thin plate adapted to rest freely upon the table top beneath the table cloth, two mating terminals of considerable diameter, one projecting and the other recessed whereby they are self centering and one supports the other, one of said terminals being mounted on the cap and the other on 50 the plate, and a second pair of coöperating

terminals, one carried by the cap and the other by the plate, said second pair of terminals being in position to engage each other when the mating terminals are in engagement, supply conductors connected to the 55 terminals on the plate, and connectors for the table appliance connected to the terminals on the cap.

5. In a multiple connector for electrical appliances adapted to be used upon a cloth-covered dining table, a plate adapted to rest upon the table top, a pair of supply conductors leading to said plate, a conical terminal connected to one of said supply conductors, an annular terminal connected 60 to the other of said supply conductors, said terminals being mounted upon said plate, a countersunk terminal adapted to rest upon said conical terminal, the conical terminal and countersunk terminal being of large diameter, spring fingers adapted to engage the annular terminal when the counter bored terminal is resting upon the conical terminal, and a plurality of connectors for energizing 65 the table appliances, the respective poles of 70 said connectors being electrically connected respectively to the counter bored terminal and to the spring fingers aforesaid.

6. In a multiple connector for electric appliances to be used upon a dining table, a metallic dome having a plurality of connectors for energizing the table appliances, a counter bored terminal fastened face downward inside of the dome, a base plate adapted to underlie the tablecloth and rest freely 80 upon the table, a pair of supply conductors leading to said plate, a peaked terminal connected to one of the supply conductors and pointing upward from the plate and adapted 85 to support the counter bored terminal, a second terminal on said plate connected to the remaining supply conductor, and a spring terminal mounted within said dome adjacent to the counter bored terminal and adapted to engage the second terminal on 90 the plate when the counter bored terminal is resting upon the peaked terminal.

In witness whereof I have hereunto subscribed my name.

JOHN F. GILCHRIST.
